DESIGN FOR A LOUD-SPEAKING TELEPHONE

Gabriel M. Giannini, North Hollywood, Calif., assignor, by mesne assignments, to Associated Electric Laboratories, Inc., Chicago, Ill., a corporation of Delaware

Application January 21, 1942, Serial No. 105,340

Term of patent 14 years

To all whom it may concern:

Be it known that I, Gabriel M. Giannini, a citizen of the United States of America, residing at North Hollywood, county of Los Angeles, California, have invented a new, original, and ornamental Design for a Loud-Speaking Telephone, of which the following is a specification, reference being had to the accompanying drawing forming a part thereof.

Fig. 1 is a front perspective view, and Fig. 2 is a rear perspective view of a loud-speaking telephone, showing my new design.

I claim:

The ornamental design for a loud-speaking telephone, as shown.

GABRIEL M. GIANNINI.
